BRUSH CLEANER FOR FLOORS AND WALLS

Marshall Herron, Sacramento, Calif.

Application October 6, 1950, Serial No. 12,475

Term of patent 14 years

(Cl. D9—2)

To all whom it may concern:

Be it known that I, Marshall Herron, a citizen of the United States, residing in the city of Sacramento, county of Sacramento, State of California, have invented a new, original, and ornamental Design for a Brush Cleaner for Floors and Walls, of which the following is a specification, reference being had to the accompanying drawing, forming part thereof in which the figure is a perspective view of a brush cleaner for floors and walls embodying my new design.

The side and end of the brush which are not disclosed in the drawing are identical respectively with the side and end which are disclosed.

I claim:

The ornamental design for a brush cleaner for floors and walls, as shown and described.

MARSHALL HERRON.
